UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,835**, dated September 2, 1873; application filed August 9, 1873.
[Term of Patent 3½ years.]

Q.

To all whom it may concern:

Be it known that I, FREDERICK WINK, of the city and county of Philadelphia, State of Pennsylvania, have invented a Design for Shawl-Pattern, of which the following is a specification:

The nature of my design for a striped shawl-fabric is fully illustrated by the accompanying drawing, in which—

Figure 1 is a diagram, showing the relative arrangement of the two stripes A and B of which the pattern is composed; Fig. 2, a view of one-half of the stripe A; and Fig. 3, a view of the stripe B.

The stripe A is composed of an ornamental central bar, *a*, of a narrower ornamental bar, *b*, and of a series of parallel wide and narrow plain bars or ribs, all of a character so clearly

shown in the drawing as to require no minute description. The stripe B has a central rib, *d*, of the same character as that of the stripe A, and is otherwise composed of parallel minor stripes, bars, or ribs, arranged as shown.

Irrespective of the colors employed, I claim—

1. The design for the stripe A, as shown and described.

2. The design for the whole pattern, including the stripes A and B.

In testimony whereof I have signed my name to this specification in the presence of two subscribing witnesses.

FRED. WINK.

Witnesses:

CLINTON M. LATOURETTE,
LEWIS T. GODFREY.
